United States Patent Office.

WILLIAM F. ROSSMAN, OF HUDSON, NEW YORK.

Letters Patent No. 106,410, dated August 16, 1870.

STOVE-PIPE DAMPER.

The Schedule referred to in these Letters Patent and making part of the same.

To all whom it may concern:

Be it known that I, WILLIAM F. ROSSMAN, of the city of Hudson, in the county of Columbia and State of New York, have invented a new and useful Improvement in the Construction of a Draught-Damper for retarding and shutting off or arresting the draughts of stove and furnace-pipes and flues; and I do hereby declare that the following is a full, clear, and exact description of the construction and operation of the same, reference being had to the annexed drawing making a part of this specification, in which—

Figure 1 is a perspective view of my improved damper complete, with its several parts combined.

Figure 2 is a longitudinal view of the inner side of the handle half of the spindle of said damper.

Figure 3 is a longitudinal view of the exterior of the opposite half of the spindle of said damper, the inner side being perfectly flat and plain.

Figure 4 is a longitudinal view of the edge or side of spindle, the two parts, figs. 1 and 2, combined.

My invention relates to the construction of a damper, with spindle, composed of two parts, and these parts corresponding with and fitted to each other in such a manner as to securely embrace the damper-plate, and to be easily inserted in and removed from the pipe.

My damper-plate A will be of the form of the interior of the pipe in which it is to be inserted; but as the circular is most commonly used, I shall confine my description, for the most part, to that form.

The circular plate A I perforate in the line of its diameter with a series of prick-punch holes, sufficient to raise burs on the opposite side, and about half an inch apart.

The spindle (see figs. 1 and 2) is composed of two half-round pieces of cast-iron, so made as to correspond with and fit each other, and to embrace the circular plate A in the middle or line of its diameter, (see fig. 1)

The half of the spindle, fig. 2, is provided with a cross-head of any suitable form or device, to constitute a handle.

On its inner or flat side it is provided with a longitudinal groove or depression, g, with occasional interruptions or cross-bars d d d.

It is also provided with a crease or neck, e e, fig. 2, for receiving the edge of the pipe.

The other half, p, (see fig. 3,) fits into the space e at the handle-end, between the two raised edges or flanges b b.

The two together form a round rod or spindle, which may be easily cut or made of any required length to suit the size or diameter of the pipe or flue wherein it is to be placed.

For the purpose of inserting this damper, a hole of proper size for the spindle is punched through opposite sides of the pipe, same as for inserting any ordinary damper.

The handle half of spindle (see fig. 2) is first inserted through these holes, so that the groove or crease e e receives the margin or edge of the pipe surrounding the hole.

The damper-plate A is then laid onto this half within the pipe, the line of burs or punch-holes corresponding with the groove g, with bur side down. These burs lying along in this groove, when the other half, p, fig. 3, is inserted, keep the plate in its place, and prevent the spindle from sliding out.

The little cross-bars d d d in the groove g also prevent the spindle from sliding either way.

The other half, p, fig. 3, is inserted at the handle end between the flanges b b, flat side down, and passed through the hole f, on the opposite side of the pipe.

The damper is now complete; but if the spindle should at any time require tightening in the holes in the pipe, a metallic wedge may be inserted between the half p, fig. 3, and the plate A, thus separating the two parts of the spindle, so as to cause them to bear a little more against the margins of the holes in the pipe.

What I claim as my invention, and desire to secure by Letters Patent of the United States, is—

1. A damper, provided with spindle, composed of two parts, figs. 1 and 2, constructed as, or substantially as, and for the purpose herein set forth.

2. The combination and arrangement of plate A and the two parts of the spindle, represented by figs. 2 and 3, substantially in the manner and for the purpose herein set forth.

WM. F. ROSSMAN.
